DAVID H. COX, OF ROSELLE, NEW JERSEY.

AUTOMOBILE MARKER-BRACKET.

1,074,838.

Specification of Letters Patent.

Patented Oct. 7, 1913.

Application filed April 18, 1911. Serial No. 621,958.

To all whom it may concern:

Be it known that I, DAVID H. COX, a citizen of the United States, and resident of Roselle, in the State of New Jersey, have invented certain new and useful Improvements in Automobile Marker-Brackets, of which the following is a specification.

My invention relates to automobile marker brackets. One type of these brackets and that to which my present invention particularly relates is adapted to be supported in position at the front side of the radiator at the front end of an automobile by means of an arm or other part of the bracket having a clamped connection with the so-called "cap" at the top of the radiator. These radiator caps, as well known, comprise a short length of tubing brazed or similarly secured at one end to the wall of the radiator tank at the opening therein through which the water is entered and at their upper end being screw-threaded for the detachable connection therewith of a cover or cap proper. As the distance of these caps from the front or face side of the radiators vary in different sizes and makes of cars, the marker bracket, in order to be made in one size that will be readily adaptable to the various sizes and makes of cars, is so formed as to project some distance forward of the face side of the radiator when attached to the radiator cap. As thus supported, however, the bracket is subjected to considerable vibration during the running of the car and it has been found that this is sufficient to frequently result in loosening and breaking the supporting radiator cap from its connection with the radiator. Because of this it has been the object of my invention to provide an improved bracket of the type referred to having means that will be operative to support the bracket against undue vibration and so remove the strain exerted by it on the supporting radiator cap.

To this end, the invention in a preferred form thereof, consists in providing the bracket with a rearwardly projecting bearing member for engagement with the face side of the radiator, and which bearing member will preferably be adjustable to vary its distance of projection according to the space between the bracket and the radiator; the said bearing member being coöpera-

tive with the bracket attaching means to hold the bracket in substantially fixed relation to its support.

Referring now to the accompanying drawings forming part of this specification, in which—

Figures 1, 2 and 3 are a side elevation, top plan and front elevation respectively, of a radiator and its cap having attached thereto a marker bracket embodying my invention. Figs. 4 and 5 are views similar to Fig. 2 showing different forms of my invention. Figs. 6 and 7 are enlarged bottom and rear views respectively, of the marker bracket shown in Figs. 1, 2 and 3. Fig. 8 is an enlarged sectional detail of a cap forming part of the bracket bearing member.

Similar reference characters indicate like parts in the several figures of the drawings.

The radiator is indicated generally at 2 and its cap at 3. These parts may be of any usual form and construction.

The marker bracket is here shown as comprising a horizontally-arranged arm 4 adapted for the detachable connection therewith of a marker, such as indicated at 5, and a second arm 6 ranging upwardly and rearwardly from the arm 4 for detachable connection with the radiator cap 3; said arm 6 being here shown as provided at its upper end with a clamping collar 7 for effecting rigid connection of the bracket with said cap 3.

The extent of projection of the upper attaching end of the arm 6 rearwardly of the arm 4 is sufficient to cause the latter, when the bracket is attached to the radiator cap, to project some distance forward of the face side of the radiator as shown; the extent of space between the arm 4 and the radiator varying in different cars according to the distance of the supporting cap from the face side of the radiator. The bracket being thus supported at only one end, its depending marker-carrying end is of course subjected to considerable vibration during the running of the car, and this, as hereinbefore stated, is sufficient to frequently result in the loosening and breaking of the supporting radiator cap from its connection with the radiator. To prevent this, I have provided the bracket near its lower end with a rearwardly projecting bearing member for

engaging with the face side of the radiator and thereby coöperating with the bracket attaching means to hold the bracket in substantially fixed relation to its support. This bearing member may be of any desired construction suitable for the purpose and it will also preferably be adjustable to vary its distance of projection from the bracket according to the space between the bracket and the radiator. This means, as shown in the several figures of the drawings other than Figs. 4 and 5, consists of an arm 8 projecting from the rear side of the bracket and being screw-threaded at its end for the adjustable connection therewith of a cap 9, which latter will bear against the face of the radiator. By turning this cap on the arm 8 in the proper direction its distance from the bracket may be varied to cause it to bear tightly against the radiator, and after being so adjusted it may be secured in adjusted position by a lock-nut 10.

As shown in the several figures other than Figs. 4 and 5, only one bearing member 8—9 is employed and that is located at the center of the bracket arm 4. If desired, however, two such members may be employed which will be located near the opposite ends of the arm 4 as shown in Fig. 4. In Fig. 5 I have shown another form of bearing member. In this case the bearing member is made of wire bent to assume a widened U-shaped form, the base 11 of which bears against the radiator while its two arms 12, 12, project through the slots 13, 13, of the bracket arm 4 and have an adjustable connection therewith by means of fastening nuts 15, 15. If desired, that part of the bearing member having direct contact with the face of the radiator may be provided with some soft yielding material to prevent marring of the paint or varnish on the radiator. For instance, the part 9 might be provided with an insert of rubber or similar material, as indicated at 16 in Fig. 8, or the part 11 might be provided with a covering of rubber hose or other yielding material as indicated at 17 in Fig. 5.

What I claim is:—

1. A marker bracket for automobiles 50 adapted to be rigidly connected to and supported by the radiator cap in a position forward of the radiator, said bracket extending downwardly below the radiator cap, and adjustable means projecting rearwardly 55 from the bottom of the bracket and adapted to bear against said radiator without connection therewith to prevent vibration of the bracket.

2. A marker bracket for automobiles 60 comprising an arm having a clamp at one end adapted to be rigidly connected to and supported by the radiator cap, said arm extending forwardly and downwardly in front of the radiator with a space therebetween, and rigid means projecting rearwardly from the lower end of the arm adapted to bear only against the radiator to hold the bracket relatively thereto and prevent vibration of the same, said means having an adjustable end 70 to vary the bearing pressure against the radiator.

3. A marker bracket for automobiles comprising a rigid integral arm having a clamp at one end for firmly and removably connecting the bracket to the radiator cap, said arm projecting forwardly and downwardly 75 in front of the radiator with a space therebetween, and adjustable means mounted on the rear of the arm at its lower end adapted 80 to press on the radiator to hold the bracket against vibration.

4. A marker bracket for automobiles having a rearwardly projecting arm at one end provided with a terminal clamp, and also 85 having a rearwardly projecting stud, and a bearing member mounted adjustably on said stud whereby its distance of projection from the bracket may be varied.

Signed at New York, in the county of 90 New York, and State of New York, this 5th day of April, A. D. 1911.

DAVID H. COX.
